GAME BOARD

Joachim Berger, 20 Bahnhofstr., 52 Siegburg, Germany
Filed Jan. 13, 1971, Ser. No. 106,315
Term of patent 14 years
Int. Cl. D21—01

U.S. Cl. D34—5

The drawing figure is a plan view of a game board showing my new design. The board is of conventional thickness.

The characteristic feature of my design resides in the particular pattern formed by the contrasting colored blocks on the board.

I claim:

The ornamental design for a game board, as shown and described.
